Primary Examiner — David Muller*Assistant Examiner* — Nathan Johnston(74) *Attorney, Agent, or Firm* — McDonnell Boehnen Hulbert & Berghoff LLP(57) **CLAIM**

The ornamental design for a mounting block, as shown and described.

DESCRIPTION

FIG. 1 is a top perspective view of a mounting block in accordance with the present design.

FIG. 2 is a bottom perspective view thereof;

FIG. 3 is a side perspective view thereof;

FIG. 4 is a side perspective view thereof;

FIG. 5 is a side elevation view thereof;

FIG. 6 is a top plan view thereof; and,

FIG. 7 is a bottom plan view thereof.

The broken line showing of mounting block is included for the purpose of illustrating portions of the "article" and forms no part of the claimed design.
